ELECTRIC RAZOR

Bernd Rohrbach, Kettenhofweg 80,
Frankfurt am Main, Germany

Filed Jan. 20, 1971, Ser. No. 108,240

Claims priority, application Germany July 24, 1970

Term of patent 14 years

Int. Cl. D28—03

U.S. Cl. D95—3

Fig. 1

Fig. 5

Fig. 2

Fig. 3

FIG. 1 is a side elevational view of an electric razor, showing my new design, the diametrically opposite side being substantially a mirror image thereof.

FIG. 2 is another side elevational view thereof, with the razor turned 90° in one direction from the view of FIG. 1;

FIG. 3 is still another side elevational view of the razor, with the razor turned 180° from the view of FIG. 2;

FIG. 4 is a top plan view; and

FIG. 5 is a bottom plan view thereof.

I claim:

The ornamental design for an electric razor, as shown and described.
